UNITED STATES PATENT OFFICE.

CLEMENT V. FLOYD, OF KANSAS CITY, MISSOURI.

DESIGN FOR A CASE FOR VENDING-MACHINES.

SPECIFICATION forming part of Design No. 34,926, dated August 13, 1901.

Application filed July 8, 1901. Serial No. 67,551. Term of patent 3½ years.

To all whom it may concern:

Be it known that I, CLEMENT V. FLOYD, a citizen of the United States, residing at Kansas City, in the county of Jackson and State of Missouri, have invented and produced a certain new and original Design for Cases for Vending-Machines; and I do declare the following to be a full, clear, and exact description of the invention, such as will enable others skilled in the art to which it appertains to make and use the same.

The invention relates to a new and original design for a case for a vending-machine; and it consists of the design shown in the accompanying drawings, in which—

Figure 1 is a perspective view, and Fig. 2 is a side view.

The leading feature of the design comprises the back piece 1, the side pieces 2, the for-

ward edges of which are straight from *a* to *b*; 20 thence curved outwardly from *b* to *c*, thence straight from *c* to *d*, thence bowed outwardly from *d* to *e*, thence straight from *e* to *f*, where they meet a horizontal base *g* and horizontally-disposed side cleats *h*, the horizontally-disposed cap-piece *i*, the panel *j*, the glass panel *k*, having a rectangular offset *l*, and a bulged panel *m*, having an open pocket *n*.

What I claim is—

The design for a case for a vending-machine, 30 as herein shown and described.

In testimony whereof I have hereunto set my hand in presence of two subscribing witnesses.

CLEMENT V. FLOYD.
